(57) **CLAIM**

The ornamental design for a formed metal boat steering wheel rim with finger grip indentations, as shown and described.

DESCRIPTION

FIG. 1 is a top perspective view of the steering wheel rim with finger grip indentations showing my new design, a representative center hub and spokes typically associated with a boat steering wheel being shown in phantom;

FIG. 2 is a bottom perspective view of the steering wheel rim with finger grip indentations formed on the underside thereof, the finger grip indentations being formed with a compound curvature, curved radially and circumferentially, into the oval-shaped steering wheel rim, the representative center hub and spokes as depicted in FIG. 1 being shown in phantom lines;

FIG. 3 is an enlarged, partial, bottom perspective view similar to that shown in FIG. 2, but enlarged to show more detail of the finger grip indentations formed therein, a portion of the representative center hub and spokes being shown in phantom;

FIG. 4 is a further enlarged, partial, top perspective view similar to that shown in FIG. 1;

FIG. 5 is an enlarged, cross sectional view of the steering wheel rim taken through a finger grip indentation, the oval shape of the steering wheel and the compound curvature of the finger grip indentations being best depicted; and,

FIG. 6 is an enlarged, cross sectional view of the steering wheel rim taken through a ridge between adjacent finger grip indentations, the oval shape of the steering wheel being best depicted.
